UNITED STATES PATENT OFFICE.

THOMAS G. NICHOLSON, OF CHICAGO, ILLINOIS.

FLOOR CONSTRUCTION.

1,427,625.

Specification of Letters Patent. Patented Aug. 29, 1922.

Application filed December 6, 1920. Serial No. 428,659.

To all whom it may concern:

Be it known that I, THOMAS G. NICHOLSON, a citizen of the United States, residing at Chicago, in the county of Cook and State 5 of Illinois, have invented certain new and useful Improvements in Floor Constructions, of which the following is a specification.

This invention relates to a fire-proof floor construction in which tile blocks and concrete beams are arranged between suitable 10 supporting beams.

It is my object to construct a floor wherein the beams support between them an arch 15 that is formed of a plurality of tile blocks, each similar to the others; a floor wherein the tiles composing each arch are arranged in rows that are reinforced by concrete beams at desired intervals; a floor wherein a skew of concrete is arranged between the 20 end tiles and the beam proximate thereto; and a floor wherein are carried soffet tiles beneath each beam, the supporting means therefor serving also to prevent concrete from entering the cells of the adjacent end 25 tiles.

Other objects and purposes of this invention, as will more clearly hereinafter appear, are also in contemplation.

In the accompanying drawings is shown 30 an exemplification of my invention in the manner following:

Figure 1 is a horizontal section through a portion of floor taken approximately on line 1—1 of Fig. 2;

Fig. 2 is a transverse section thereof taken approximately on line 2—2 of Fig. 1; and

Fig. 3 is a similar view taken on line 3—3 of Fig. 2.

In the construction of the present floor use 40 is made of steel I-beams A set apart at desired intervals to support between them an arch which, according to this invention, consists of tiles B arranged in rows B', B², B³, etc., with concrete C in the form of beams C', C², etc., arranged preferably between each two rows of tiles, as best shown in Fig. 1. Upon the arch thus constructed may be 45 arranged the usual filler tiles D (whenever the depth of the I-beams would require this) supporting a layer E of concrete wherein are set strips F to which the floor boards G are fastened.

The arch formed in the manner just described comprises a number of rows of tiles 50 each of which is in the form of a rectangular block of standard construction. The sev-

eral tiles in the arch shown in Fig. 2 are numbered individually as 5, 6, 7, 8, and 9, and, as is usual, may be hollow to provide interior cells 10 (see Fig. 3). The tiles thus 60 arranged in rows are suitably adhered together as at 11 by means of mortar, and by preference these tile rows are arranged in groups of two with a concrete beam C', C², etc., intervening. The end tiles which are 65 similar to the others abut a skew H of concrete which fills in the space between the lower flange 11' and web 12 of the I-beam and the proximate face of the end tile block 5 or 9, as the case may be. This concrete 70 skew, as appears best in Fig. 1, is united with each concrete beam C', C², etc., so as to entirely surround the tile rows both on their ends and sides. The pouring of the concrete in this manner is facilitated by the 75 use of small channel tiles I, each facing upward, one tile being provided for each concrete beam, so that the resulting ceiling will present an all tile surface. A desirable reinforcement for each concrete beam is afforded by the use of a rod or wire J which may, if desired, lie within the channel tile, the ends of the rod terminating in or close 80 to the skew, as shown in Fig. 2.

Each tile arch is preferably depressed 85 slightly below the lower flange 11 of the I-beam on the under side of which are supported soffet tiles K. These soffets may be supported as by means of a wire mesh 15 which extends beneath each soffet with its 90 ends carried upwardly as far as desired to lie in the skew of concrete. By extending the ends of the mesh upward sufficiently to cover the ends of some or all of the cells 10, the concrete may be prevented from entering 95 into the end tiles.

It will be observed that the construction herein described makes use of rows of tile blocks each of which may be of the same general shape so as to form an arch extending between a pair of I-beams. Throughout the length of each row the several tiles present their ends squarely against each other, while the ends of each row abut the skew of concrete, thus providing an arch which 100 is capable of opposing end thrusts such as result from the imposition of a load thereupon. By a construction such as this, I dispense with the use of specially formed tiles such as keys, skewers, etc., using instead 105 only rectangular blocks of the kind that are commonly designed for partitions. This, of

course, is a great advantage both in regard to cost of material and expense of installation. It is further of advantage to employ a greater number of tile rows than concrete beams, this being rendered possible by forming the concrete beams integral with the skew so that the one derives reinforcement from the other. In this manner a considerable saving is effected in the cost of material, and time of construction, as well as in the weight of the floor.

I claim:

1. A floor construction wherein is combined spaced I-beams, an arch extending between each two I-beams, each arch consisting of a transversely arranged concrete beam below which is a channel tile, in association with a row of tile blocks, each the same in form as the others, the tile row being arranged transversely between the I-beams in parallel and adjacent relation to the concrete beam, and a skew of concrete disposed between the end tiles of the row and the proximate I-beam, the ends of the concrete beam uniting with the skew, substantially as described.

2. A floor construction wherein is combined spaced I-beams arranged in parallelism, a longitudinally extending soffet tile beneath the lower flange of each I-beam, upwardly facing channel tiles arranged transversely between the soffet tiles at desired intervals, a rod aligned with each channel tile and having its ends adjacent the web of the I-beam, and over each channel tile a beam of concrete which also is extended adjacent the I-beams to form a skew, means for supporting each soffet tile consisting of an element engaged therewith and extending into the concrete skew, and tile arches between the I-beams arranged adjacent the several concrete beams, substantially as described.

3. A floor construction wherein is com-

bined spaced I-beams arranged in parallelism, a longitudinally extending soffet tile beneath the lower flange of each I-beam, upwardly facing channel tiles arranged transversely between the soffet tiles at desired intervals, and over each channel tile a beam of concrete which also is extended adjacent the I-beams to form a skew, means for supporting each soffet tile consisting of an element engaged therewith and extending into the concrete skew, and tile arches between the I-beams arranged adjacent the several concrete beams, substantially as described.

4. A floor construction wherein is combined spaced I-beams between which is extended a tile arch with its ends abutting a skew of concrete which lies adjacent each beam, the tile arch being composed of a number of tiles arranged in double rows, and a concrete beam intervening between each two rows of tile and having its ends united with the skew, soffet tiles arranged below the I-beams as well as below the concrete beam in flush relation with the under side of the tile arch, the soffets being suspended from concrete forming the skew and beam, substantially as described.

5. A floor construction wherein is combined spaced supporting beams on the opposite sides of which are formed concrete skews, an arch extended transversely between the beams and composed of a plurality of tile blocks having cells therein arranged longitudinally of the arch, soffet tiles carried below the supporting beams, and means supporting the soffet tiles extending into the concrete skew and over the open end of the cells of the adjacent tile blocks, said means serving to prevent entrance of the concrete thereinto, substantially as described.

THOMAS G. NICHOLSON.
